United States Patent Office

Des. 186,693
Patented Nov. 17, 1959

186,693

WASTE PAPER BASKET

Mansoor K. Haghani, New York, N.Y.

Application June 18, 1959, Serial No. 56,415

Term of patent 14 years

(Cl. D58—4)

Fig. 1 is a plan view of a waste paper basket embodying my new design.

Fig. 2 is a front elevational view thereof, the rear view being identical thereto.

Fig. 3 is a side elevational view thereof, the other side elevational view being identical thereto.

I claim:

The ornamental design for a waste paper basket, as shown.
